Inventor:

Charles K. Pickles,
by Robert Burns Atty.

UNITED STATES PATENT OFFICE.

CHARLES K. PICKLES, OF ST. LOUIS, MISSOURI, ASSIGNOR TO SAMUEL M. DODD, OF SAME PLACE.

STEP-OVER CAR-SEAT.

SPECIFICATION forming part of Letters Patent No. 613,423, dated November 1, 1898.

Application filed December 13, 1897. Serial No. 661,722. (No model.)

To all whom it may concern:

Be it known that I, CHARLES K. PICKLES, a citizen of the United States, residing at St. Louis, in the State of Missouri, have invented 5 certain new and useful Improvements in Step-Over Car-Seats; and I do hereby declare the following to be a full, clear, and exact description of the same, reference being had to the accompanying drawings, forming a part 10 of this specification.

The present invention relates to car-seats, and more especially to that type of car-seats in which the seat-back has a step-over movement in its reversal action over the seat portion, while said seat portion has a movement 15 in unison with the seat-back, but in an opposite direction, to afford in each position full seating capacity and a proper slope of the seat with relation to the back, an example of 20 which may be found in my former application for Letters Patent, Serial No. 655,815, filed October 20, 1897.

The objects of the present improvements are to provide a simple, durable, and effective 25 connecting mechanism between the seat or chair parts, whereby the shifting movement that is imparted to the seat proper is amplified to an extent that will expose for effective use the full width of the seat from front to 30 back and with which the relative movements of the parts are attained in a certain and positive manner, as will hereinafter more fully appear. I attain such objects by the construction illustrated in the accompanying 35 drawings, in which—

Figure 1 is an end elevation of a step-over car-seat embodying the present invention, one position of the step-over back being shown in full lines and the other position in 40 dotted lines; Fig. 2, a detail longitudinal section at line x x , Figs. 3 and 6; Figs. 3 and 4, detail sectional elevations at lines x' x' and x^2 x^2 , Fig. 6; Fig. 5, a side view of one of the shaft-hangers of the intermediate gearing in 45 a detached condition; Fig. 6, a detail plan view of the mechanism at one end of the car-seat, the back-arms being shown in section at line x^3 x^3 , Fig. 3.

Similar numerals of reference indicate like 50 parts in the several views.

Referring to the drawings, 1 represents the seat portion, of any usual construction and provided at each end with end plates 2, each of said plates being formed with a horizontal toothed rack 3, preferably of a rectilinear 55 form, and with a horizontal supporting slot or recess 4, preferably of a curved or segmental nature, as shown.

The chair base or support will be of any usual and approved construction and in the 60 present invention will be provided with end plates 5, each of which is provided with a toothed rack 6, preferably of a curved or segmental nature, with a horizontal confining slot or recess 7, preferably of a curved nature 65 and concentric with the toothed rack 6, and with supporting projections or studs 8, that have engagement in the supporting slot or recess of the seat-plate 2 to support and limit the seat in its shifting movement. Such 70 shifting movement of the seat portion is a combined sliding and tilting movement in a direction opposite to that in which the seat-back 9 has movement. The amount of such tilting movement of the seat will depend upon 75 the amount of curvature given to the supporting slot or recess 4 in the end plate of the seat portion, so that by modifying the form of said slot or recess a corresponding 80 change will be made in the movement of such seat portion.

9 is the step-over seat-back, preferably of the straight form shown, and finished or upholstered on both sides or surfaces.

10 are the supporting-arms of the seat-back 85 9 and which, as in my aforesaid prior application, may be of a substantially counterpart formation, with their upper ends having pivotal connection with the arms of a cross-head 11, attached to the respective ends of the 90 seat-back 9, as shown, while their lower ends are provided with guide studs or projections 12 and with sector-shaped ends 13, concentric with the guide studs or projections 12 and preferably of a toothed nature, as shown, and 95 adapted to engage and move upon the correspondingly-formed track on toothed rack 6 on the end plate of the chair standard or base in a manner similar to the construction as shown and claimed in my aforesaid prior ap- 100

plication, the engagement of the parts being such that the lower ends of the back-supporting arms will move in the same direction as the upper ends thereof, so that the arms may 5 be of a shorter nature than the arms heretofore employed in the present class of step-over car-seats.

In the present improvement the sliding movement of the seat portion 1 in a direction 10 opposite to that of the seat-back, as heretofore described, is attained in an indirect manner by the following mechanism:

14 is a shaft-hanger formed with eyes or orifices 15 at each end, that have engagement 15 with the studs or projections 12 on the supporting-arms 10 of the seat-back and with an intermediate orifice 16, that forms a bearing for the shaft 17, extending from end to end of the seat and supported at the end by a 20 counterpart arrangement. 18 are pinions at the respective ends of said shaft, that have engagement with the respective toothed sector-shaped ends 13 of the back-supporting arms 10 to receive motion therefrom and at 25 the same time connect the same together, so as to move in unison in a positive manner. 19 are gear-wheels of a larger diameter than the pinions 18, also secured to the respective ends of the shaft 17 and adapted to engage 30 with the toothed racks 3 upon the seat portion 1. With this construction the shaft 17, with its gear-wheels and pinions 19 and 18, moves from side to side with the sector-shaped ends of the supporting-arms 10 in a reversal 35 of the car-seat, and the difference in the relative diameters of the pinions 18 and gear-wheel 19 governs the amount of shifting movement imparted to the seat portion 1, so that by a relative change in such diameters 40 a corresponding change can be attained in the amount of the shifting movement of said seat portion 1.

Having thus fully described my said invention, what I claim as new, and desire to secure 45 by Letters Patent, is—

1. In a step-over car-seat, the combination of a base or standard, provided with a track, a shifting seat portion, a step-over back, means for supporting said back comprising 50 concurrently-moving arms at each end of the seat adapted to bear and have rolling movement from side to side upon the track of the standard, means whereby the lower ends of said arms are caused to travel in the same direction as the upper ends thereof, and means actuated by the movement of the back-supporting arms and adapted to shift the seat portion in a direction opposite to the movement of the back, substantially as set forth.
2. In a step-over car-seat, the combination of a base or standard provided with a toothed track, a shifting seat portion a seat-back, back-supporting arms provided with toothed sector-shaped ends adapted to travel from 55 one side to the other upon said track, means whereby the lower ends of said arms are caused to travel in the same direction as the

upper ends thereof, and an intermediate mechanism between the back-supporting arms and the seat portion for imparting to 70 the seat portion a shifting movement in a direction opposite to the travel of the back, substantially as set forth.

3. In a step-over car-seat, the combination of a base or standard provided with a toothed 75 track of a segmental form, a shifting seat portion, a seat-back, back-supporting arms provided with toothed sector-shaped ends adapted to travel from one side to the other upon said tracks, means whereby the lower 80 ends of said arms are caused to travel in the same direction as the upper ends thereof, and an intermediate mechanism between the back-supporting arms and the seat portion for imparting to 85 the seat portion a shifting movement in a direction opposite to the travel of the back, substantially as set forth.

4. In a step-over car-seat, the combination of a supporting base or standard provided with a toothed track, a shifting seat portion, 90 a seat-back, back-arms provided with toothed sector-shaped ends adapted to travel from one side to the other upon said back, and an intermediate mechanism between the back-arms and the seat portion for imparting to 95 the seat portion a shifting movement in a direction opposite to the travel of the back-arms the same comprising an intermediate pinion gearing with the toothed sector ends of the arms, a gear-wheel turning with said pinion, 100 and a rack upon the seat portion engaging said gear-wheel, substantially as set forth.

5. In a step-over car-seat, the combination of a supporting base or standard provided with a toothed track, a shifting seat portion, 105 a seat-back, back-arms provided with toothed sector-shaped ends adapted to travel from one side to the other upon said track, and an intermediate mechanism between the back-arms and the seat portion for imparting to 110 the seat portion a shifting movement in a direction opposite to the travel of the back-arms the same comprising an intermediate pinion gearing with the toothed sector ends of the arms, a gear-wheel turning with said pinion, 115 and a rack upon the seat portion engaging said gear-wheel, and a longitudinally-arranged shaft carrying said gear and pinion, substantially as set forth.

6. In a step-over car-seat, the combination 120 of a supporting base or standard provided with a toothed track, a shifting seat portion, a seat-back, back-arms provided with toothed sector-shaped ends adapted to travel from one side to the other upon said track, and an intermediate pinion gearing with the toothed 125 sector ends of the back-arms, substantially as set forth.

7. In a step-over car-seat, the combination of a supporting base or standard provided 130 with toothed tracks, a shifting seat portion, a seat-back, back-arms provided with toothed sector-shaped ends adapted to travel from one side to the other upon said tracks, interme-

diate pinions gearing with the toothed sector ends of the back-arms at the respective ends of the car-seat, and a longitudinally-arranged shaft carrying said pinions, substantially as set forth.

8. In a step-over car-seat, the combination of a supporting base or standard provided with a toothed track, a shifting seat portion, a seat-back, back-arms provided with toothed sector-shaped ends adapted to travel from one side to the other upon said track, an intermediate pinion gearing with the toothed sector ends of the back-arms, and a hanger for said pinion, connected to said arms by studs that are concentric with the sector ends thereof substantially as set forth.

9. In a step-over car-seat, the combination of a supporting base or standard provided with toothed tracks, a shifting seat portion, a seat-back, back-arms provided with toothed sector-shaped ends adapted to travel from one side to the other upon said tracks, intermediate pinions gearing with the toothed sector ends of the back-arms at the respective ends of the car-seats, a longitudinally-arranged shaft carrying said pinions, and hangers for said shaft connected to the back-arms by studs that are concentric with the sector ends thereof, substantially as set forth.

10. In a step-over car-seat, the combination of a supporting base or standard provided with supporting studs or projections, a shifting seat portion provided with horizontal supporting slots or recesses engaging the supporting studs or projections on the seat-stand-

ard, a seat-back, and means for imparting motion to the shifting seat portion, substantially as set forth.

11. In a step-over car-seat, the combination of a supporting base or standard provided with supporting studs or projections, a shifting seat portion provided with horizontal supporting slots or recesses of a segmental nature engaging the supporting studs or projections on the seat-standard, a seat-back, and means for imparting a shifting motion to the shifting seat portion, substantially as set forth.

12. In a step-over car-seat, the combination of a supporting base or standard provided with supporting studs or projections, a shifting seat portion provided with horizontal supporting slots or recesses of a segmental nature engaging the supporting studs or projections on the seat-standards, a seat-back, back-arms provided with toothed sector-shaped ends adapted to travel from one side to the other, a toothed track upon the standard upon which the arm ends travel, an intermediate pinion gearing with the toothed sector ends of the arms, a gear-wheel turning with said pinion, and a rack upon the seat portion engaging said gear-wheel, substantially as set forth.

In testimony whereof witness my hand this 11th day of December, 1897.

CHARLES K. PICKLES.

In presence of—

ROBERT BURNS,
G. A. PENNINGTON.
